UNITED STATES PATENT OFFICE.

LOUIS V. ARONSON, OF NEWARK, NEW JERSEY.

DESIGN FOR A TEMPERATURE-INDICATOR FOR AUTOMOBILE-RADIATORS.

56,578.

Specification for Design.

Patented Nov. 16, 1920.

Application filed March 31, 1920. Serial No. 370,351. Term of patent 14 years.

To all whom it may concern:

Be it known that I, LOUIS V. ARONSON, a citizen of the United States, residing at Newark, in the county of Essex and State of New Jersey, have invented a new, original, and ornamental Design for Temperature-Indicators for Automobile-Radiators, of which the following is a specification,

reference being had to the accompanying drawing, forming part thereof, in which—

Figure 1 is a plan and Fig. 2 a side view showing my new design.

I claim:

The ornamental design for a temperature indicator for automobile radiators, as shown.

LOUIS V. ARONSON.
